UNITED STATES PATENT OFFICE.

ALFRED B. MORSE, OF SOUTH EASTON, MASSACHUSETTS.

SEWING-MACHINE-THREAD UNWINDER.

SPECIFICATION forming part of Letters Patent No. 318,923, dated May 26, 1885.

Application filed December 12, 1884. (No model.)

To all whom it may concern:

Be it known that I, ALFRED B. MORSE, of South Easton, county of Bristol, State of Massachusetts, have invented an Improvement in 5 Sewing-Machine-Thread Unwinders, of which the following description, in connection with the accompanying drawing, is a specification, like letters on the drawing representing like parts.

10 This invention has for its object to provide a simple and easily-operated device by which to unwind thread, the said device being readily applicable directly to the spool containing the thread which is to be unwound.

15 My improved device consists, essentially, of a sleeve, the foot of which is inserted into the open center of the spool, the said sleeve receiving a spindle, to which is rigidly attached the unwinding-arm, preferably formed of wire 20 coiled about the spindle, and brazed or soldered thereto, such construction enabling light-weight spring-wire to be used for the unwinding-arm, and yet afford a very strong and durable connection with the spindle.

25 The drawing represents one of my thread-unwinders applied to a spool of thread, the spool being shown broken out to better display the spindle.

The spool A, containing thread to be used 30 in a sewing-machine, is bored centrally, as usual, and will be held in place when in use by placing the lower end of the spool on a pin in any usual manner. The sleeve B of my improved unwinding device has a foot, b, which is of suitable diameter to enter the central 35 bore or hole at the top of the spool; and to enable the said sleeve to be retained in position with relation to the spool I have slotted the foot, and placed in the said slot a spring, b', one end of which is left free. A part of the 40 said spring normally extends outward beyond the periphery of the foot, where it acts frictionally against the spool to prevent the withdrawal of the sleeve, except by the exertion of 45 considerable force. The foot never rotates in the spool, and may be applied readily to any usual spool. The upper end of the sleeve is bored to receive the spindle c, which at its upper end is provided with a thread-guiding

50 eye, c'. The spindle near its lower end is provided with an annular groove, c², which receives a pin, e, by which to keep the spindle in the sleeve, but yet enable the spindle to rotate freely. The thread-unwinding arm d, made preferably of fine steel wire, has at its 55 lower end a thread-receiving eye, d', the upper end of the said wire being wrapped in one or more coils about the spindle, to which it is brazed or soldered, such method of connecting the unwinding-arm with the spindle being 60 very strong, and enabling a small wire to be used for the arm d. Thread from the spool is conducted through the eye d', thence through the eye c' to the usual thread-guide eyes and tension device of the sewing-machine with 65 which the spool is to be used. The shoulder b² of the sleeve meets the end of and prevents the entrance of the foot b too far into the spool.

I claim—

1. The sleeve of the thread-unwinding device, adapted to be inserted into a spool, and bored at its end for the reception of a spindle, combined with a spindle inserted therein provided with a guide-eye, and having a spring-wire arm, d, provided with a guide-eye, and 75 coiled about and soldered or brazed to said spindle, substantially as described.

2. The sleeve provided with the foot to enter the spool, and with a spring to engage the spool, and with a hole for the reception of the 80 spindle, combined with the spindle having a thread-guiding eye, and with the spring-arm having a thread-guiding eye, substantially as described.

3. The sleeve having the foot to enter the 85 spool, and the spindle entered into the said sleeve, combined with the spring-arm, it having a thread-guiding eye at one end, and coiled at its other end about the spindle, substantially as described.

In testimony whereof I have signed my name to this specification in presence of two subscribing witnesses.

ALFRED B. MORSE.
